CLAIM

We claim the ornamental design for the robot for testing electric energy meter, as shown and described.

DESCRIPTION

FIG. 1 is a front view of a robot for testing an electric energy meter according to the present application;

FIG. 2 is a rear view of the robot for testing an electric energy meter according to the present application;

FIG. 3 is a left view of the robot for testing an electric energy meter according to the present application;

FIG. 4 is a right view of the robot for testing an electric energy meter according to the present application;

FIG. 5 is a top view of the robot for testing an electric energy meter according to the present application;

FIG. 6 is a first perspective view of the robot for testing an electric energy meter according to the present application;

FIG. 7 is a second perspective view of the robot for testing an electric energy meter according to the present application;

FIG. 8 is an enlarged view of circle 8 of FIG. 1 of the robot for testing an electric energy meter according to the present application;

FIG. 9 is an enlarged view of circle 9 of FIG. 1 of the robot for testing an electric energy meter according to the present application;

FIG. 10 is an enlarged view of circle 10 of FIG. 3 of the robot for testing an electric energy meter according to the present application;

FIG. 11 is an enlarged view of circle 11 of FIG. 3 of the robot for testing an electric energy meter according to the present application;

FIG. 12 is an enlarged view of circle 12 of FIG. 3 of the robot for testing an electric energy meter according to the present application;

FIG. 13 is an enlarged view of circle 13 of FIG. 4 of the robot for testing an electric energy meter according to the present application; and,

FIG. 14 is an enlarged view of circle 14 of FIG. 4 of the robot for testing an electric energy meter according to the present application.
